UNITED STATES PATENT OFFICE.

DANIEL DRAWBAUGH, OF EBERLY'S MILLS, PENNSYLVANIA.

IMPROVEMENT IN MILLSTONES.

Specification forming part of Letters Patent No. 38,296, dated April 28, 1863.

To all whom it may concern:

Be it known that I, DANIEL DRAWBAUGH, of Eberly's Mills, in the county of Cumberland and State of Pennsylvania, have invented certain new and useful Improvements in the Manner of Hanging, Balancing, and Driving Millstones; and I do hereby declare the following to be a full, clear, and exact description of the same, reference being had to the accompanying drawings, making a part of this specification, in which—

Figure 1 represents a top plan of a portion of the bed-stone with the spindle and driving-arms, also a portion of the runner with the balance and driving rynd shown in red lines. Fig. 2 represents a vertical section through the runner and bed-stone, and showing the mode of connecting the driving-arms with the balance-rynd.

It is most common to use but two driving-arms on the spindle, though I am aware that four have been used for the purpose of preventing the runner from having an irregular motion. I use four driving-arms for that purpose also; but, as heretofore arranged, the object was not fully attained, because the least wear of one arm prevented it from exerting the same force as the others, and, consequently, there was not uniformity in the motion of the runner, and they would wear unevenly. It is necessary for a perfectly-true motion that each driving-arm should exert the same force on its portion of the runner, and to arrive at this I do not actually connect the arms and balance or driving rynd, but simply overlap or interlock them, so that by set-screws each arm may be made to bear against the rynd, and thus practically give them uniform driving force or effect.

To enable others skilled in the art to make and use my invention, I will proceed to describe the same with reference to the drawings.

The spindle A passes through the bed-stone B in the usual manner, and upon a squared portion, C, of the spindle the driving-arms D D

D D, four in number, are arranged. These arms D, at their outer ends, are formed, as shown in Fig. 1, so as to lap over or interlock with recesses a, made in the balance or driving rynd E, so that set-screws b may pass through the ends of the arms D and bear against the rynd E, as shown in said Fig. 1. By this arrangement the runner I is driven at four points diametrically opposite each other, and with the same uniform force at each point, and so dividing the force around the stone as to prevent it from tipping in the least injurious degree, and if at any time there should be any irregularity it may be corrected by moving the set-screws so that all shall touch their respective points of impact at the same time.

To apply this principle of driving to millstones not originally prepared for it, I make an opening in the crown of the two rynd, or at their crossing-point, in which a pin, F, is placed, having a head or shoulder upon it, by which pin the runner is supported on the point of the spindle G. As the stone wears away the pin may be changed for another with a different-sized head, so as to keep this bearing point uniformly at or near the center of the stone, in which position it works the best. The rynd are recessed into the runner in the usual way, as shown at H.

What I claim is—

1. In combination with the driving-arms and the rynd, the set-screws for making uniform and equal contact between them, and thus regulate the driving-force at all four points of contact, substantially as and for the purpose described.

2. Supporting the runner on the top of the spindle by means of a removable or adjustable pin or plug for the purpose of preserving this point of suspension as near the center of the stone as it wears away as possible, substantially as described.

DANL. DRAWBAUGH.
